Primary Examiner — T Chase Nelson

(57) **CLAIM**

The ornamental design for a sole for footwear, as shown and described.

DESCRIPTION

The file of this patent contains at least one drawing/photograph executed in color. Copies of this patent with color drawing(s)/photograph(s) will be provided by the Office upon request and payment of the necessary fee.

1. Sole for footwear

1.1 : Perspective

1.2 : Front

1.3 : Back

1.4 : Right

1.5 : Left

1.6 : Top

1.7 : Bottom

The reproductions show a sole for a right item of footwear, the sole for a corresponding left item of footwear being the mirror image of the one shown in the reproductions. The portion of the design shown in the color red is for the purpose of illustrating portions of the sole and forms no part of the claimed design.
